COMBINED BOTTLE AND CAN OPENER AND ICE CHOPPER TOOL

Karl Brocken, Riviera Beach, Fla.

Application August 3, 1954, Serial No. 31,721

Term of patent 7 years

(Cl. D44—29)

FIG. 1.

FIG. 2.

FIG. 3.

FIG. 4.

To all whom it may concern:

Be it known that I, Karl Brocken, a citizen of the United States, residing at Riviera Beach, Florida, have invented a new, original, and ornamental Design for a Combined Bottle and Can Opener and Ice Chopper Tool, of which the following is a specification, reference being had to the accompanying drawing, forming a part hereof.

Fig. 1 is a plan view of a combined bottle and can opener and ice chopper tool embodying my new design;

Fig. 2 is a side view thereof;

Fig. 3 is a front end view; and

Fig. 4 is rear end view.

I claim:

The ornamental design for a combined bottle and can opener and ice chopper tool, substantially as shown.
